O. F. Eckard

INVENTOR

Victor J. Evans

WITNESS:

ATTORNEY

UNITED STATES PATENT OFFICE.

OBED F. ECKARD, OF HICKORY, NORTH CAROLINA.

OIL CAN.

Application filed March 30, 1925. Serial No. 19,424.

To all whom it may concern:

Be it known that I, OBED F. ECKARD, a citizen of the United States, residing at Hickory, in the county of Catawba and State 5 of North Carolina, have invented new and useful Improvements in Oil Cans, of which the following is a specification.

This invention relates to improvements in valves for use in cans and the like and contains 10 temlates the provision of a novel form of valve which is arranged within the bottom of a can and which includes a valve operating rod which extends through the upper cover of the oil can and which includes such 15 spring compression means therein as will readily and easily seat the valve.

Another object of the invention is to provide a valve casing upon and within the bottom of the oil can and which extends below 20 the bottom an appreciable distance and which owing to its position adjacent one side of the can, may be readily and easily placed over the breather cap of an internal combustion engine and upon pulling the 25 valve rod upwardly the valve will then be opened and cause the oil to drain into the breather cap.

With the above and other objects in view, the invention further includes the following 30 novel features and details of construction, to be hereinafter more fully described, illustrated in the accompanying drawing and pointed out in the appended claims.

In the drawing:—

Figure 1 is an elevation of a can in section and showing the relative position of the valve, valve casing and valve operating rod therefor.

Figure 2 is a vertical sectional view taken 40 on line 2—2 of Figure 1.

Figure 3 is a similar view taken on line 3—3 of Figure 1 and showing the construction of the valve operating means.

Referring to the drawing in detail, wherein like characters of reference denote corresponding parts, the reference character 10 indicates an oil can of the usual and ordinary construction which includes a raised bottom 11 and top 12, all of the above is of 45 the usual and well known construction and forms no part of the present application for Letters Patent but is merely shown for purposes of illustration in bringing forward the novel advantages of the above entitled invention. The invention residing in the provision of a tubing 13 including an enlarged

upper portion 14 which further includes a valve seat 15 adjacent the upper periphery and inner side thereof, the purpose of the valve seat 15 will be presently apparent. 60 Extending inwardly from the inner sides of the tubing 13 is an annulus 16 including a substantially offset upwardly extending apertured collar 17 formed integral therewith and having its apertured portion 65 aligned centrally of the casing 13. The lower end 18 of a valve rod 19 extends through the apertured portion of the collar 17 and annular flange 16 an appreciable distance and includes adjacent the lower end 70 thereof, a pin member 20 arranged transversely thereof and extending outwardly upon the outer side walls of the valve rod 19 an appreciable distance in order that a compression spring 21 which encircles 75 the lower end 18 of the valve rod 19 below the apertured collar 17 and annular flange 16 will be held upon the lower end 18 of the valve rod 19 and have its opposite ends tensioned against the outer side of the apertured collar 17 and the upper side of the pin 20 whereby the valve rod 19 will be normally tensioned downwardly.

Arranged upon the valve rod 19 and encircling the same is a composition valve 22 which may be formed of any pliable substance such as rubber, fabric and the like and which is adapted to be snugly seated within the valve seat 15 provided in the upper periphery 14 of the tubing or casing 13 and held normally seated through the spring action of the compression spring 21. In order to provide means upon the valve rod 19 for holding the valve 22 upon the valve rod 19 at a suitable point and to prevent the same from sliding or reciprocating upon the valve rod 19 and hold the same rigid so that the same will reciprocate with the valve rod 19 as an integral part thereof, I provide a pin 23 which extends transversely through the valve rod 19 at an appreciable distance above the upwardly extending integrally formed collar 17 on the annular flange 16 and which pin 23 has interposed therebetween and the under side 100 of the valve 22, a washer or spacing element 24 in order to prevent the downward movement of the valve 22 upon the valve rod 19. In order to provide means upon the valve rod 19 for restricting the movement of the valve 22 in an opposite direction thereon, I provide a lock washer 25 which encircles 105

the valve rod 19 and engages the upper side of the valve 22 and which is in turn held against accidental displacement and reciprocation upon the valve rod 19 through the 5 instrumentality of a jamb nut 26 threaded to the valve rod 19. It will thus be noted that the valve 22 is held rigidly upon the valve rod 19 and will be normally seated within its seat 15 provided in the tubing or 10 casing 13 through the instrumentality of the compression spring 21. The upper portion of the valve rod 19 extends through an opening 27 provided in the top 12 of the can 10 and also through a casing 28 having a restricted entrance opening 29 provided in the 15 lower end thereof and a relatively large attaching flange 30 upon the upper periphery thereof and which may be welded or otherwise secured to the under side of the 20 top or cover 12 of the can 10. Encircling the valve rod 19 within the casing 28 is a compression spring 31 which has its upper end engaging the under side of the cover or top 12 of the can 10 and its opposite end 25 tensioned against a pin 32 extending transversely of and outwardly an appreciable distance from the valve rod 19. Fixed to the valve rod 19 upon the upper and adjacent the outer end thereof is a jamb nut 33 which 30 includes a disk, washer or the like 34 which engages the upper side thereof, encircling the valve rod 19 and normally lying flush with the upper side or top of the cover 12 of the can 10.

35 Mounted upon the outer and upper free end of the valve rod 19 is a disk 35 which forms a hand or finger engaging portion in order that the valve rod may be easily lifted, or reciprocated in order that the 40 valve 22 may be selectively disengaged and closed within its seat 15 and owing to the multiple arrangement of the compression springs 21 and 31 respectively it will be noted that the valve 22 will be seated and 45 held against accidental displacement.

50 In the mode of operation of the present invention, it will be clearly apparent that this valve rod when raised will compress the retractile springs 21 and 31 respectively and in so doing the valve 22 will be unseated within its valve seat 15 and that the washer or disk 34 and jamb nut 33 included upon the upper and outer portion of the valve rod 19 will also be lifted upwardly in a similar 55 manner with the valve 22 and in so doing the oil or other substance contained within the can 10 will be caused to drain through the casing or tubing 13 in the manner set forth. When releasing the disk or hand 60 hold 35 provided upon the upper and outer end of the valve rod 19, it is manifest that the valve rod when moving downwardly will cause the disk or lock washer 34 to engage the upper side of the top or cover 12 of the 65 can 10 in such a manner as to limit the

downward movement of the valve 22 within its seat 15 in order that the spring tension exercised or stressed upon the valve 22 within its seat 15 will be so limited so that the valve will not be cut or mashed or in any 70 way warped in order that the same will always be as effective as originally. This washer 34 and jamb nut 33, it will be noted will restrict the downward movement of the valve 22 within its seat in order to prevent 75 this great difficulty.

The invention is susceptible of various changes in its form, proportions and minor details of construction, and the right is 80 herein reserved to make such changes as properly fall within the scope of the appended claims.

Having thus described my invention what is claimed is:—

1. An oil can of the character described 85 having a tubular casing extending through the can bottom an appreciable distance, said casing having an upper enlarged portion which includes a beveled valve seat upon the upper periphery and inner sides thereof, a valve rod, a valve mounted upon the valve rod, means included upon the valve rod and upon the opposite sides of the valve for rigidly securing the same thereto, a casing provided upon the under side of the can 90 top and receiving the upper end of the valve rod therethrough, means included adjacent the upper end of the valve rod and upon the outer side thereof and engaging the upper and outer side of the can top 100 for restricting the movement thereof, means included upon the upper and outer free end of the rod for facilitating the lifting of the same, and spring compression means included in the lower and upper casings for 105 normally seating the valve.

2. An oil can of the character described comprising a tubular casing extending through the can bottom an appreciable distance, said tubular casing having an upper 110 enlarged portion including a beveled valve seat upon the upper periphery and inner sides thereof, an annular flange arranged centrally and extending inwardly from the bore of the tubular casing, an apertured collar formed integral upon the upper sides of the annular flange and having its aperture aligned centrally of the tubular casing bore, a valve rod extending through the tubular casing and the apertured collar, a compression spring encircling the lower end 115 of the valve rod and engaging the under side of the apertured collar, a valve rigidly secured upon the valve rod and normally seated through the instrumentality of the compression spring, a tubular casing secured to the under side of the can top and including a restricted entrance opening in the lower end thereof and receiving the upper end of the valve rod therethrough, a 120

compression spring arranged within the casting and encircling the valve rod and normally compressing the same downwardly therein, a disk member rigidly secured upon the upper portion of the valve rod and normally engaging the upper side of the can top, and means included upon the upper free end of the valve rod to facilitate the raising and lowering of the valve rod in the opening and closing of the valve within the 10 seat substantially as set forth.

In testimony whereof I affix my signature.

OBED F. ECKARD.
